ELECTRIC SIGN

Frank G. Davenport, Chicago, Ill., assignor to
 A. C. Davenport and Son, Inc., Chicago, Ill., a
 corporation of Illinois

Application May 15, 1941, Serial No. 393,520

2 Claims. (Cl. 40—132)

The present invention relates in general to electric signs, and more in particular to such electric signs as include an illuminated panel adapted for use in displaying words, messages and the like by means of removable letters or characters.

The object of the invention is to provide an electric sign of the foregoing character which is adapted for installation in factories and other industrial establishments in connection with safety campaigns initiated and carried on for the general purpose of accident prevention. This is a subject which has received much attention in recent years, and some excellent results as regards reduction in the number and seriousness of accidents have been obtained, but safety campaigns have always been handicapped by the difficulty of sustaining the interest of the employees. Thus a given campaign may produce good results at the start, but due to a lagging interest the employees become careless and the unhealthy condition prevails until interest is revived by a fresh crop of accidents.

In consequence of the foregoing there has long been a demand for some means by which a safety campaign can be made more effective, particularly from the standpoint of sustaining the interest of the employees and preventing the recurrent let-downs with their toll of accidents which have been the rule heretofore. The need for full effectiveness of safety measures is especially great at the present time, in view of the large number of inexperienced employees who are being trained in the various industrial occupations.

The present invention is designed to meet the requirements outlined above and to provide a sign or display panel which will keep the idea of safety first constantly before the employees with a variety of slogans, messages, and the like which will sustain interest and effectively prevent the employees from forgetting the rules promulgated for the purpose of accident prevention.

The invention will be more fully described hereinafter in connection with the accompanying drawings, in which—

Fig. 1 is a front view of an electric sign constructed in accordance with the invention;

Fig. 2 is a side view of the same sign;

Fig. 3 is another front view, with certain parts cut away and with the display panel partly withdrawn from the casing;

Fig. 4 is a section on an enlarged scale, taken on the line 4—4, Fig. 1;

Fig. 5 is a section on the line 5—5, Fig. 1;

Fig. 6 is a view of the display panel, in perspective; and

Fig. 7 is a diagrammatic circuit drawing showing how the lamps and other circuit elements are connected.

Referring to the drawings, and particularly to Fig. 1, it will be seen that the sign comprises a generally upright casing which is closed in front by plates or panes of glass 1, 2, and 3. The panes 1 and 2 are substantially square and together occupy about one-third of the front of the casing. The pane 3 is rectangular and occupies the remaining space beneath the panes 1 and 2.

The plates or panes 1 and 2 are preferably made of colored glass, pane 1 being colored red, while pane 2 is colored green. Those parts of the panes which lie outside the circles are made opaque by painting with black paint, as are the letters of the words "Safety" and "First", which appear within the circles. Means is provided for illuminating the colored panes to display the words thereon, as will be described presently.

The rectangular plate or pane of glass 3 is transparent and lies in front of a display panel to be presently described on which the messages or slogans "Start from scratch" and "Get first aid" appear. This panel is also illuminated so as to display the words appearing thereon.

The casing is made of sheet metal, such as tin plate, for example. The back of the casing is made in one piece and comprises a portion 5 which is parallel to the front of the casing, two sloping portions 6 and 7, and a side portion 8 which is perpendicular to the front of the casing.

On the side opposite side 8, see Fig. 5, there is an opening; that is, the back portion 7 is not extended forward to the front of the casing but is folded over as indicated at 9. The folded edge at 9 forms the right hand margin of the opening, which extends vertically from the bottom of the casing to a point just above the upper edge of the glass pane 3. It will be seen, therefore, that the casing is completely closed on the left hand side, as seen in Fig. 3, for example, whereas on the right hand side there is an opening through which the display panel may be withdrawn.

At the front of the casing there are four vertical strips 13 to 16, inclusive, which are each made by folding a metal strip along a central line parallel to its edges to give the strip a substantially U-shaped cross-section. The four strips are shown clearly in Fig. 1 and also in the sectional view, Fig. 5. The edge of portion 8 of the back of the casing is received in the folded metal

strip 13, to which it may be secured by soldering at several points. On the opposite side of the casing the edge of a rectangular sheet 11 is received in the folded metal strip 16, see Fig. 2, and is soldered to the strip 16 and also to the portion 7 of the back of the casing. The sheet 11 closes the casing at the right side thereof, except for the opening below, which has previously been referred to.

The vertical strips 13 to 16, inclusive, are rigidly connected together at the top and bottom, respectively, by means of folded metal strips 17 and 18, which are seen in section in Fig. 4. The strips are preferably soldered together at their intersections. There is also a folded metal strip 19, which divides the front of the casing horizontally, and a folded metal strip 20 which divides the upper part of the front of the casing vertically. The strip 19 may be soldered to vertical strips 14 and 15, while strip 20 may be soldered together at their intersections. There is also a folded metal strip 19, which divides the front of the casing horizontally, and a folded metal strip 20 which divides the upper part of the front of the casing vertically. The strip 19 may be soldered to vertical strips 14 and 15, while strips 20 may be soldered to the horizontal strips 17 and 18.

The metal strips described in the foregoing may be given a bright finish and form an ornamental frame or frames for the glass panes 1, 2, and 3. In order to add to the attractiveness of the design, strips 21 and 22 of colored semi-transparent plastic material such as cellulose acetate may be inserted in the guides formed by the two pairs of vertical folded metal strips 13-14 and 15-16. Alongside the panes 1 and 2 the colored strips 21 and 22 are preferably covered by opaque strips 23 and 24, which may be strips of metal inserted in the guides like strips 21 and 22.

The bottom of the casing is closed by a metal sheet 25. The rear edge of this sheet is bent down at right angles and is received in the folded lower edge of the back parts 5-8. The front edge of the sheet 25 is also bent down at right angles and is soldered to the vertical strips 13-16. The construction will be clear from Fig. 4.

At the top of the casing there is an ornamental sheet metal plate 26, which can be seen in Figs. 1 and 4. The lower edge of plate 26 is soldered to the back side of the horizontal strip 17. The top of the casing is closed by the cover 27, which is provided with hinges such as 28.

The opening at the side of the casing, which has previously been mentioned, is normally closed by a sliding door or cover plate 12. At the lower end the plate 12 is received in a guide which is formed in the metal sheet 30. This sheet 30 is soldered to the bottom plate 25, is bent downward at 31, and is bent upward at 32, whereby a groove or channel is formed between the parts 31 and 32, which are properly spaced in accordance with the thickness of the cover plate 12, as indicated in Fig. 5. There is a similar guide or channel for the upper end of the cover plate 12, as indicated at 33, Fig. 2. It will be clear that the cover plate may be removed by sliding it to the rear.

The display panel comprises a rectangular frame having top and bottom members 35 and 36 and side members 37 and 38. These parts may be secured together in any suitable manner, as by soldering. There are also a plurality of double channel cross members 39 which extend horizontally between the side members 37 and 38 to which they are secured by soldering. The cross

members 39 are H-shaped in cross-section, as seen in Fig. 4. In order to support the cross members at the center a vertical rod 40 is provided, as shown in Fig. 6, and is soldered to the top and bottom members 35 and 36 and to the cross members 39.

The frame is closed by a plurality of strips of white translucent plastic material such as cellulose acetate, indicated at 41, which are carried on the cross members 39. The strips 41 are slightly wider than the space between two adjacent cross members and consequently they assume a curved formation when they are assembled in position. The strips 41 form a translucent background for the letters which are mounted on the display panel.

The letters may be painted on rectangular sheets of transparent cellulose acetate and preferably are of two sizes. The larger letters such as 42, Figs. 1 and 4, are on sheets which are long enough to bridge two of the spaces between cross-members, while the smaller letters such as 43 are on sheets which are only long enough to bridge one such space. The sheets on which the smaller letters are painted are, in fact, equal in length to the width of the strips 41, and when one of these letters is mounted it assumes a curved formation in contact with the associated strip 41, as shown in the case of the letter 43. The sheets on which the larger letters are mounted are nearly twice as long, and since they bridge two spaces between cross members when mounted, they are necessarily curved forward away from the associated strips 41, as shown in the case of the letter 42. The manner in which the letters are supported on the cross members 39 will be obvious from Fig. 4, and it will not be necessary to describe in detail how they are mounted and removed. Suffice it to say that they can be changed with great facility, which makes it possible to put a fresh message on the panel in a few minutes.

The display panel is removable from the casing, as indicated in Fig. 3, where it is shown as having been partly withdrawn from the casing through the opening in the side. In order to removably mount the display panel, and also the glass pane 3 in front of it, suitable channels are provided. At the bottom there is a horizontal strip 50, having one edge bent upward at 52, which is soldered to the bottom plate 25. There is also a folded strip 51, of U-shaped cross section, which is soldered to the strip 50 and preferably also to the vertical strips such as 14. The folded strip 51 forms a guide or channel for the lower edge of the glass pane 3, and the strip 51 also cooperates with the upwardly bent edge 52 of strip 51 to form a guide or channel for the bottom of the display panel. At the top there is a strip 53, corresponding to strip 50 at the bottom, and having a downwardly bent edge 55. There is also a folded strip 54, which is secured to strip 19, as shown, and which may also be soldered to strip 53. The latter supports the forward edge of the horizontal partition 56, to which it is secured by soldering. The folded strip 54 forms a channel for the upper edge of the glass pane 3 and cooperates with the down-turned edge 55 of strip 53 to form a channel for the top of the display panel.

It will be seen that the folded strips 51 and 54 are effective to securely retain the glass pane 3, while at the same time permitting the pane to be partly or wholly withdrawn through the opening 70 at the right. The display panel is likewise se-

curely retained in the described channels, but may be withdrawn at will, being slidably in the channels. When the display panel is replaced after having been withdrawn, it is pushed back into the casing until the side 37 comes in contact with a vertical strip 57 which is provided as a stop to properly position the panel. The strip 57 has one edge bent forward at 58, as seen in Fig. 4, and is soldered to strips 53 and 50. Outward movement of the panel is prevented by two L-shaped strips 59 which are secured to the panel frame member 38 and abut against the inside of the cover plate 12 when the latter is in place.

The glass panes 1 and 2 are retained in suitable vertical channels in which the edges of the panes are received. Thus, as shown in Fig. 5, there are two vertical folded metal strips 61 and 62, of U-shaped cross-section, which are located on opposite sides of the vertical partition 60 and which are secured to the vertical strip 29, as indicated. The parts are preferably further secured by soldering, and the rear edge of the partition 60 may be soldered to the back portion 5 of the casing. It will be seen that the inner edges of the panes 1 and 2 are securely held in the channels formed by the folded strips 61 and 62. The outer edges are similarly held in vertical folded strips identical with strips 61 and 62 which are soldered to the vertical strips 14 and 15 at the back side thereof.

The display panel is illuminated by a lamp 65, which is received in a socket 66, mounted on a bracket 67 which is secured to the back of the casing on the inside. A bushed opening is indicated at 68 through which a two-conductor cord passes to the interior of the casing. A switch is indicated at 69.

The colored circular portions of the panes 1 and 2 are illuminated by means of lamps 70 and 73, respectively. These lamps are received in sockets 71 and 72 which are mounted on the vertical partition 60, as shown in Fig. 3. There is also a flashing device 74 mounted on this partition.

The circuit connections are shown in Fig. 7. The conductors 75 are conductors of the cord which leaves the casing at the bushed opening 68 and terminates in a plug for connection to a supply outlet. The switch 69 is in series with one conductor 75 and controls the supply of current to all the lamps. Lamp 65 is connected across the line and is illuminated continuously when the switch 69 is in closed position. Lamps 70 and 73 are connected in series and are illuminated alternately under control of the flashing device 74, as will be explained. This device comprises a bi-metal strip 77 and a heating winding 78, together with a contact which is closed and opened by bending of the bi-metal strip. The flashing device is connected in parallel with the lamp 70.

The operation of the improved electric sign will now be described. For this purpose it will be assumed that the sign is hung on the wall by means of the perforated suspension link 80 in the cafeteria of a factory where large numbers of employees congregate during the lunch hour. Other locations may, of course, be selected, but the one mentioned may be considered as typical. It may also be assumed that the requisite letters have been mounted on the display panel in order to form a message which it is desired to convey to the employees, such, for example, as the message shown in Fig. 1. This

message, it will be observed, is representative of a variety of messages or slogans which may be used in conducting a safety campaign.

The display panel is, of course, made up when outside of or at least partly withdrawn from the casing. When this work is finished, the display panel is slid back into the casing and the door 12 is replaced in order to close the casing. The panel is thus rendered inaccessible to persons who might be disposed to meddle with it through curiosity or mischief. If desired, a lock may be provided for the door 12, but this is not usually necessary, for the display panel is protected behind the glass pane 3, and the necessity of opening the side of the casing to gain access to the panel is sufficient to deter the casual observer from attempting to do so, even if the method of gaining such access is perceived. This arrangement thus presents a decided advantage over a fixed display panel which is unprotected in front, as the letters on such unprotected panels are accessible to all, and the temptation to change them is sometimes too great to be resisted.

The cord 75 is plugged in at a convenient outlet, and the switch 69 is thrown to its "on" position in order to start the operation of the sign. When the current is turned on, the lamp 65 becomes operative to illuminate the display panel, causing the words of the message to be displayed. Lamp 65 also illuminates the colored strips 21 and 22 at the sides of the display panel. Current is also supplied to the lamps 70 and 73, which are connected in series across the line. Lamp 70 is of higher resistance than lamp 73, a 30-watt lamp and a 60-watt lamp may be used, and consequently only lamp 70 is effectively lighted. The circular portion of the pane 1 is thus illuminated, displaying the word "Safety" which appears thereon. The flashing device 74 is connected in parallel with lamp 70 and, being of high resistance, does not shunt enough current away from the lamp to prevent it from lighting up effectively. The current flow through the heating winding 78 gradually heats up the bi-metal strip 77, which bends to the right and eventually closes the contact. By this operation the lamp 70 and the winding 78 are short-circuited, whereupon lamp 73 receives the full line voltage and is effectively lighted, lamp 70 being extinguished. Thus the circular portion of the pane 2 is illuminated and the word "First" which appears thereon is displayed. When the winding 78 is short-circuited, the heating of the strip 77 ceases, and very shortly the strip begins to cool. After cooling a certain amount, the strip straightens out enough to open the contact, whereupon the original circuit conditions are re-established, lamp 70 being lighted and lamp 73 being extinguished.

The flasher 74 continues to operate in the manner described, lighting lamps 70 and 73 alternately, to alternately display the words "Safety" and "First." The rate of operation should be fairly fast, say about 15 or 20 times per minute, which is slow enough to permit the words to be read easily and yet is fast enough to give the impression of action and call attention to the sign.

It will be seen that the words used in the upper portion of the sign are appropriate to a large variety of messages which may be set up on the display panel and that the flashing operation is effective to attract the attention of all persons in the vicinity of the sign, who are thus compelled to read the current message displayed

for their benefit. Thus far better results are secured than were attainable with previously known sign or display apparatus.

The sign may remain in operation as described for as long as desired. It is started and stopped by means of the switch 69, as will be apparent. In case one of the lamps 70 or 73 should burn out or lose its efficiency, access to the upper compartment in which the lamp is located may be had by opening the door 27 in the top of the casing. This door also affords access to the flasher 74 in case it should require attention. The lamp 65 in the lower part of the casing may be changed by partially removing the display panel and by also partly removing the glass pane 3, which affords access to the lamp from the front of the casing. The panel and pane may be withdrawn from the casing through the opening at the right side thereof, after first removing the cover plate 12, as will be clear from the preceding description.

As an aid to maintaining interest in the safety campaign, it is desirable that the message set up on the display panel be changed frequently, preferably every day. This can be done easily, in the manner previously described. It may be mentioned also that the display panel can be used for posting occasional notices which have to be brought to the attention of the employees and thus the necessity of providing the usual bulletin board is avoided. The possibility of the appearance of an important notice may be used in this way to increase the interest in the display board and help to insure that the messages carried thereby are read by all concerned.

It will be understood that the improved sign disclosed herein may be used in connection with other kinds of campaigns or promotional activities, the words displayed by the flasher apparatus being selected so as to have special signifi-

cance with respect to the messages to be carried by the display panel.

The invention having been described, that which is believed to be new and for which the protection of Letters Patent is desired will be pointed out in the appended claims.

What is claimed is:

1. In an electric sign, a casing divided into two upper compartments and a lower compartment, a transparent pane of glass closing the front of the lower compartment, a removable display panel located behind said pane and carrying the words of a message, a lamp for illuminating said panel, two glass panes closing the fronts of the two upper compartments and carrying words appropriate to the message on said panel, two lamps located in said two upper compartments, respectively, circuit means for continuously lighting the lamp in the lower compartment to display said message, and means for lighting the other two lamps alternately to display said words and thereby attract attention to said message.

2. In an electric sign, a casing divided into a plurality of small compartments and a relatively large compartment, a transparent closure for the front of the large compartment, a display panel in said casing carrying the words of a variable message, a lamp behind said panel for illuminating the same, different colored panes closing said smaller compartments and carrying unchangeable words appropriate to variations of said message, lamps for illuminating said colored panes, means for continuously lighting said first mentioned lamp to display said message, and means for lighting the other lamps successively to display the words on the said colored panes to call attention to the sign and to the message on said panel.

FRANK G. DAVENPORT.
